CORROSION-PROOF COVERS FOR PRESSURE VESSELS

Friedrich Schaefer and Wilhelm Mayer, Ludwigshafen (Rhine), Germany, assignors to Badische Anilin- & Soda-Fabrik Aktiengesellschaft, Ludwigshafen (Rhine), Germany

Application January 17, 1952, Serial No. 266,854

Claims priority, application Germany January 25, 1951

7 Claims. (Cl. 220—63)

This invention relates to corrosion-proof covers for pressure vessels intended for use as containers for corrosive materials.

In reactions which proceed under pressure and at elevated temperature and in which the material used for the manufacture of the reaction vessel is attacked, a special protection against corrosion is necessary, as for example by the use of special steels or noble metals or lead, copper or the like. While no particular difficulty is attached to providing this type of protection in the case of the cylindrical part of the pressure vessel, as it may readily be effected for example by the insertion of a corrosion-resistant lining tube or a steel tube plated with a corrosion-resistant material, it is more difficult to provide for a satisfactory protection of the cover, mainly because the cover must usually be provided with tubular attachments for the supply and discharge of the reactants. Since reactions usually take place at temperatures above 150° C., a loose lining of the cover with corrosion-resistant materials is not sufficiently secure in operation by reason of the difference in the coefficients of expansion of these materials and of the material of the cover and the consequent formation of wrinkles and cracks. An improvement can be obtained for example by a homogeneous application or brazing of the corrosion-resistant material directly to the cover, but for this purpose it is usually necessary to heat the cover and in very many cases this is difficult to carry out and is uneconomic by reason of its great weight in the case of pressure containers. In the case of annealed cover materials, it is also necessary to carry out a second annealing which in turn again has an ingenious effect on the protection against corrosion. Moreover, a direct application of the protective material to the cover has the disadvantage that a defect in the protective layer may not be observed until after marked corrosion of the cover itself has taken place, whereby at the same time an escape of reactants, as for example gases or liquids, can take place and in some cases, for example in the case of poisonous gases, this may be dangerous. Furthermore, for operational reasons, it is preferable to arrange the connecting pipes which are usually led through the cover so that they may be placed in position and removed without dismantling the cover.

We have now found that an effective protection of the cover of a pressure vessel against corrosion, a good control of the said protection and a ready exchangeability of connecting tubes without removal of the cover are possible by an arrangement as hereinafter described with reference to the accompanying drawing.

The lower side of a cover 1 of a pressure vessel is provided with a plate of corrosion-resistant material or a plate 3 plated with a corrosion-resistant material 2 which has a tubular extension 4 (or more than one such tubular extension if necessary) which projects to about the middle of the thickness of the cover 1. The plate 3 is drawn tightly against the inner surface of the cover 1

2

by tubular nut 5 and if desired by bolts 6 from the exterior. A connecting tube 7, which either consists of a corrosion-resistant material or is plated therewith, is passed from outside into the cover 1 and is tightened 5 against a seating on the tubular extension 4, which may for example be lenticular or plane, the seating being about in the middle of the thickness of the cover 1. Pressure on the seating is effected by screw pressure, for example by means of a sleeve 8 having a flange 9 and a bolt 10, the tightening preferably being such that the sleeve 8 is pressed by the bolt 10 onto a lenticular or flat seating on the tubular extension 4. The arrangement of the packing at about the middle of the thickness of the cover has the advantage that temperature differences between 10 the cover 1 and the parts 4, 5 and 8 cannot adversely affect the packing. By providing grooves 11 in the plate 3 on the side opposite to the plating 2 and vertical grooves 11 in the tubular extension 4 and the tubular nut 5, a defect in the corrosion-resistant layer may be 15 readily detected without the opportunity being given for the escape of large amounts of gas or liquid. The longitudinal grooves may also be replaced by helical grooves in the extension 4 and the tubular nut 5.

The drawing is given merely by way of example and 20 the apparatus therein shown may be modified in various respects.

What we claim is:

1. A corrosion-proof closure assembly for pressure vessels comprising a cover provided with a hole there-through, a corrosion-resistant plate on the inner surface of said cover provided with an opening in alignment with said hole, a corrosion-resistant tubular socket secured to said plate and having a cylindrically shaped bore and extending into said hole, said bore registering with said opening in said plate, a tubular nut member extending into said hole from the outer surface of said cover and engaging said socket for exerting tension on the latter, the said cover closely enclosing said socket and said nut member within said hole, the assembly of said nut member and said socket having an enlarged cylindrically shaped bore from a point intermediate the said surfaces of said cover to the outer extremity of the last-named assembly providing an annular shoulder on the assembly adjacent the bore thereof, a tube removably extending through 25 said last-named bore, an annular rim on the outer surface of said tube and adapted to seat on said shoulder, a tubular sleeve slidably surrounding said tube and adapted to abut on a surface of said rim opposed to the surface thereof adapted to seat on said shoulder, and means for causing said sleeve to bear on said rim.
2. A corrosion-proof closure assembly as defined in claim 1 wherein the plate and the tubular socket are wholly made of corrosion-resistant material.
3. A corrosion-proof closure assembly as defined in claim 1 wherein the plate and the tubular socket are provided with a corrosion-resistant plating.
4. A corrosion-proof closure assembly as defined in claim 1 additionally including bolt means for securing the plate to the cover.
5. A corrosion-proof closure assembly for pressure vessels comprising a cover provided with a hole there-through, a corrosion-resistant plate on the inner surface of said cover provided with an opening in alignment with said hole, a corrosion-resistant tubular socket secured to said plate and having a cylindrically shaped bore and extending into said hole, said bore registering with said opening in said plate, a tubular nut member extending into said hole from the outer surface of said cover and engaging said socket for exerting tension on the latter, the said cover closely enclosing said socket and said nut member within said hole, the assembly of said nut member and said socket having an enlarged cylindrically 30 35 40 45 50 55 60 65 70

shaped bore from a point intermediate the said surfaces of said cover to the outer extremity of the last-named assembly providing an annular shoulder on the assembly adjacent the bore thereof, a tube removably extending through said last-named bore, an annular rim on the outer surface of said tube and adapted to seat on said shoulder, a tubular sleeve slidably surrounding said tube and adapted to abut on a surface of said rim opposed to the surface thereof adapted to seat on said shoulder, means for causing said sleeve to bear on said rim, said plate, said socket, and said nut member each being provided with grooves on the side of each adjacent said cover, and means cooperating with said grooves providing a fluid path therefrom to the outer surface of said cover for the detection of a leak in the assembly of said plate, said socket, and said nut member.

6. A corrosion-proof closure assembly for pressure vessels comprising a cover provided with a cylindrically shaped hole therethrough, said hole having an enlarged cross-section from a point intermediate the inner and outer surfaces of said cover to the outer surface thereof providing an annular shoulder on the cover adjacent the hole, a corrosion-resistant plate on the inner surface of said cover provided with an opening in alignment with said hole, a corrosion-resistant tubular socket secured to said plate and extending into said hole and terminating at a point intermediate the said cover surfaces, the bore of said socket registering with said opening in said plate, a tubular nut member extending into said hole from the outer surface of said cover and engaging said socket for exerting tension on the latter, said nut member being adapted to be supported by said shoulder, the said cover closely enclosing said socket and said nut member within said hole, a tube removably extending through said nut member and said socket, an annular rim on the outer surface of said tube, said nut member and said rim being adapted for seating the latter on the end of said socket nearer said outer cover surface, a tubular sleeve slidably surrounding said tube and adapted to abut on a surface of said rim opposed to the surface thereof adapted to seat on said socket end, said sleeve being adjustably fastened to said cover at the said outer cover surface, and means for causing said sleeve to bear on said rim.

7. A corrosion-proof closure assembly for pressure

vessels comprising a cover provided with a cylindrically shaped hole therethrough, said hole having an enlarged cross-section from a point intermediate the inner and outer surfaces of said cover to the outer surface thereof 5 providing an annular shoulder on the cover adjacent the hole, a corrosion-resistant plate on the inner surface of said cover provided with an opening in alignment with said hole, a corrosion-resistant tubular socket secured to said plate and extending into said hole and terminating at a point intermediate the said cover surfaces, the bore of said socket registering with said opening in said plate, a tubular nut member extending into said hole from the outer surface of said cover and engaging said socket for exerting tension on the latter, said nut member being 10 adapted to be supported by said shoulder, the said cover closely enclosing said socket and said nut member within said hole, a tube removably extending through said nut member and said socket, an annular rim on the outer surface of said tube, said nut member and said rim being 15 adapted for seating the latter on the end of said socket nearer said outer cover surface, a tubular sleeve slidably surrounding said tube and adapted to abut on a surface of said rim opposed to the surface thereof adapted to seat on said socket end, said sleeve being adjustably 20 fastened to said cover at the said outer cover surface, means for causing said sleeve to bear on said rim, said plate, said socket, and said nut member each being provided with grooves on the side of each adjacent said cover, and means cooperating with said grooves providing 25 a fluid path therefrom to the outer surface of said cover for the detection of a leak in the assembly of said plate, said socket, and said nut member.
